CONTROLLER FOR CAR COUPLER AND ELECTRIC CIRCUITS

Application filed November 21, 1927. Serial No. 234,733.

In the modern type of electric cars operated in trains, the air lines and the electric train lines are automatically coupled with the mechanical coupling of the cars. The 5 electrical connections are made by means of electric couplers carried by the car couplers and provided with contact pieces adapted to engage with cooperating elements on a companion coupler when two cars are brought together. It is desirable that the contacts in the electric couplers be dead except during the time the cars are coupled together.

The object of the present invention is to provide means for insuring energization of the contacts in an electric coupler when two cars are coupled together and their deenergization at all other times.

Means are commonly provided for automatically uncoupling cars from points within the cars. A further object of the present invention is to control the energization of the contacts in an electric coupler through the controlling mechanism for uncoupling.

In carrying out my invention, I provide the switch that controls the flow of current to the electric coupler with a spring or other means that tends constantly to open it, and power closing means that can become effective only upon the coupling of two cars.

A further object of the present invention is to provide means for preventing the operation of the power means to effect an uncoupling until the switch closing means has been rendered ineffective.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a schematic representation of those parts of a car equipment necessary for understanding my invention; Figs. 2, 3 and 4 are respectively a top view, a front view and a rear view of a master controlling valve for the system; Fig. 5 is a section taken approximately on line 5—5 of Fig. 4; Fig. 6 is a section taken approximately on line 6—6 of Fig.

5; Fig. 7 is a section taken approximately on line 7—7 of Fig. 5; Fig. 8 is a view of the interlocking cams illustrated in Fig. 7, showing them in different positions than in Fig. 7; and Fig. 9 is a section through a fragment 55 of one of the air couplers carried by the car coupler.

Referring to Figs. 1 and 9 of the drawings, 1 represents a car coupler of the automatic type having an air cylinder 2 for uncoupling the same. 3 is a train pipe terminating in an automatic coupling device mounted on the car coupler. The air coupling device comprises a conduit section 4 fixed to the car coupler, and a sliding conduit section 5 that cooperates with 60 a similar element on a companion coupler in the act of coupling. The present invention is not concerned with the details of the air coupling means, and it will therefore be sufficient to say that there is in the stationary 65 conduit section 4 an outwardly seating spring pressed valve 6 provided with a stem 7 that is engaged by the inner end of the sliding conduit section when the latter is pushed back in coupling, to cause the valve to open. There 70 is a pipe 8 connected to the conduit section 4 outwardly from the valve. Therefore no air can enter the pipe 8 when the valve is closed, namely when cars are not in coupled relation to each other; but, when two cars are brought 75 together and coupled, so that the valve 6 is opened, air enters the pipe 8 from the train pipe 3. Air supplied by the pipe 8 is utilized to effect the operation of the uncoupling mechanism and the closing of the switch in 80 the conductors leading to the electric coupler. The rear end of the electric coupler is indicated at 9, and the controlling switch therefor at 10. 11 is an air cylinder containing 85 a piston whose stem 12 serves to close the switch when air is introduced into the cylinder. Normally the switch is held open by a spring 13 behind the piston.

The pipe 8, a pipe 14 leading to the uncoupling cylinder 2, and a pipe 15 leading to the switch cylinder 11 all are connected to the casing 16 of a master valve.

The valve casing contains three chambers, 17, 18 and 19; the chamber 17 being at the top and in the middle while the chambers 18 and 100

19 are arranged slightly below and at opposite sides of the chamber 17. The pipe 8 is connected with the chamber 17, and the pipes 14 and 15 are connected respectively to the chambers 18 and 19. Between the chamber 17 and each of the other chambers is a plug valve, these being indicated at 20 and 21. Suitable ports and passages are provided so that each of the chambers 18 and 19 may be placed in communication with the chamber 17 or shut off therefrom. The parts are so proportioned and arranged that when the valves are turned ninety degrees from the positions in which they connect the chamber 17 with the chambers 18 and 19 they vent the chambers 18 and 19 through suitable ports 22 and 23 respectively, leading to atmosphere.

It will thus be seen that air may be admitted from the pipes 8 to the uncoupling cylinder and to the switch cylinder. However, the pipe 8 is not supplied with air, that is compressed air, except when two cars are coupled together. Therefore, when the car coupler is not coupled to a companion coupler, the spring in the switch cylinder is free to operate the switch so as to open the same, or to hold it open if it is already open. When a plurality of cars are coupled together, all of the pipes corresponding to the pipes 8, except those associated with a coupler at each end of the train, will receive air, so that the switches and the uncoupling mechanism corresponding to those couplers that are in coupled relation to each other may be operated.

The two valve elements in the master valve should be interlocked to insure that the system will always function in the manner desired. As heretofore explained, each plug valve in one position vents the cylinder controlled by it to atmosphere while, in another position, ninety degrees removed, it connects that cylinder to the supply pipe 8. Each valve is provided with an operating handle, as indicated at 24 and 25, respectively, adapted to swing through an angle of ninety degrees, corresponding to the necessary movements of the plug valves. The air pipes enter the valve casing from the rear and the valve stems 26 and 27 project out through the front wall of the main portion of the casing. This front wall is hollowed out on the outer side to provide a chamber 28. Within this chamber are located two interlocking plates 29 and 30 mounted on the valve stems 26 and 27, respectively, so as to be rotatable with the latter. The plate 29 is L-shaped, being mounted on the valve stem at the juncture of the two arms. The plate 30 is in the form of a disc having two peripheral notches 31 and 32, forming arcs struck about the center of the stem 26 when these notches lie directly opposite the stem. The radius of the notch 31 is greater than that of the notch 32 and is approximately equal to or slightly greater than the radius of the

curved end of the arm 33 of the plate 29. The arm 34 of the member 29 is longer than the arm 33. Consequently the arm 33 will be free to swing in the notch 31 when the parts are in the position shown in Fig. 8; but the arm 34 is too long to swing through either notch. However, the marginal portion of the member 30, on the underside and along the notch 32, is cut away, and the outer end of the arm 34 is also cut away along the top to form a lip 35 that will ride underneath the lip on the member 30 when the parts are positioned as shown in Fig. 7; the main portion of the arm 34 being short enough to pass through the notch 32.

When the handles 24 and 25 are in the position shown in full lines in the drawings, the valves and the interlocking plates are in the position shown in Figs. 5, 6 and 7. Namely, the port 36 in the valve 20 places the chamber 18 and therefore the pipe 14 in communication with atmosphere through the port 22, so that the unlocking cylinder on the car coupler is free from pressure. At the same time the port 37 in the valve 21 places the chambers 19 and 17, and therefore the pipes 15 and 8 in communication with each other. Assuming that the car coupler is not coupled to another coupler, there will be no pressure in the pipe 8, as this pipe is venting through the open end of the slideable conduit section 5 of the air coupling device. As a result, there will be no pressure in the switch cylinder and the switch will be held open by the spring. When two cars are coupled together, air is automatically supplied to the pipe 8, as heretofore explained, and therefore air will pass from this pipe through the master valve and to the switch cylinder so as to close the switch; pressure being maintained in the switch cylinder as long as the cars are coupled.

During this time the switch controlling valve and the uncoupling valve are interlocked as shown in Fig. 7, so that the former cannot be operated, whereas the uncoupling valve may be turned through an angle of forty-five degrees, in the clockwise direction as viewed in Fig. 7. When it is desired to uncouple, the handle 24 is swung up as far as it will go, namely forty-five degrees, to the position shown in dotted lines in Figs. 3 and 4. This brings the locking plate 29 into the position shown in Fig. 8, but does not permit air to pass into the uncoupling cylinder. Thereupon the handle 25 may be swung down from the full line position as shown in Figs. 3 and 4, to the dotted line position shown in these figures, bringing the plate 30 into the position shown in Fig. 8. The switch valve 21 has now been swung through an angle of ninety degrees in the counterclockwise direction as viewed in Fig. 6, and therefore the chamber 19 and consequently the pipe 15 in the switch cylinder, are vented to atmos-

phere through the port 23. Therefore, because of the venting of the switch cylinder, the switch is permitted to open before air can be admitted to the uncoupling cylinder.

5 After the condition just explained has been brought about, the uncoupling valve may be turned through a further angle of forty-five degrees, the arm 33 of the interlocking plate 29 swinging through the slot 31 in the plate 30 during this movement of the valve. When the uncoupling valve is turned forty-five degrees the second time it causes the passage 36 to place the chamber 18 and therefore the pipe 14 in communication with the chamber 17, so that air flows from the pipe 8, through the master valve, and into the uncoupling cylinder. When the cars are drawn apart, after being uncoupled, the valve 6 in the train line closes, so that the pipe 8 vents to atmosphere through the open end of the sliding conduit section 5 on the coupler, and the air is therefore exhausted from the uncoupling cylinder.

As a protective measure, the master valve should be locked against tampering by an unauthorized person. The common method of protecting controlling devices is to make their handles removable. On account of the interlocking elements between the two valves in the master valve, it is sufficient that one of the handles be removable. To this end, while the handle 25 is made a permanent part of the master valve, the handle 24 is detachable. In the arrangement shown, the chamber 28 on the front side of the valve casing is closed by a cover plate 40. The wall 41 bounding the upper side of the chamber 28, and one of the end walls 42 are made comparatively thick and are so shaped as to provide between them and the cover plate a narrow slot 43 through which the handle 24 may be inserted. In one end of this handle is a notch 44 to receive the projecting square or rectangular end of the valve stem 26. The handle is provided with a laterally-projecting pin 45, as best shown in Fig. 5, adapted to ride in a curved groove 46 in the front face of the walls 41 and 42, to prevent accidental withdrawal of the handle. Near the lower end of the groove is a lateral branch 47 leading to the outside. When the handle 24 is in the position shown in full lines in Fig. 4 and in dotted lines in Fig. 7, the pin is opposite the notch or branch groove 47, and the handle may be withdrawn lengthwise. The interlocking of the handle 24 with the casing has the further function of preventing the removal of the handle except when the uncoupling valve is in a position to vent the uncoupling cylinder to atmosphere, thus preventing air from being admitted to the uncoupling cylinder when the cars are coupled and air automatically supplied to the chamber 17 in the master valve casing.

65 After the cars have been uncoupled and

the trainman desires to remove the detachable handle, it is first necessary for him to return the handle 24 to the position shown in full lines in Figs. 4 and 5 and in dotted lines in Fig. 7. However, in returning the handle to this position he must also return the other handle from the dotted line position in Fig. 4 to the full line position in that figure. That this follows will be clear from the inspection of Fig. 8. The uncoupling handle 24 cannot be swung in the counterclockwise direction from the position shown in Fig. 8 without first turning the handle 25 and the locking disc 30 in the counterclockwise direction through an angle of ninety degrees, since the lip 35 strikes against the edge of the plate 30, in the position shown. After the valves have been brought into the position shown in Fig. 6, with the handle 25 projecting up and the handle 24 removed, the handle 25 is locked against movement until the handle 24 is again inserted and swung up through an angle of forty-five degrees.

In order to insure that neither of the two controlling handles will be swung through an angle of more than ninety degrees, I prefer to make the slot 43 approximately ninety degrees long, thus limiting the swinging movements of the handle 24; and to provide the cover plate of the casing with stationary lugs 48 and 49 lying in the path of travel of a finger or projection 50 on the inner side of the handle 25, thereby definitely limiting the swinging movement of the handle 25.

It will thus be seen that I have produced a simple and novel means for controlling the switch associated with conductors leading to the electric coupler, as well as the uncoupling of cars; whereby the switch is caused to open before uncoupling is possible; and whereby the master controller may be left in a safe condition by the removal of a single handle. It will also be seen that while I guard against uncoupling while the contacts in the electric coupler are alive, means are provided for permitting the electric switch to be operated at will. For this purpose it is only necessary to swing the uncoupling handle up forty-five degrees to its intermediate position, bringing the interlocking plates or cams into the positions shown in Fig. 8; whereupon the controlling valve for the switch is left free to move from either limit to the other. This is important because it may at times be necessary to inspect an electric coupler while cars are coupled, and it is not desirable that the contacts in the electric coupler be energized at such times.

While I have illustrated and described with particularity only a single preferred form of my invention, I do not desire to be limited to the exact structural details thus illustrated and described; but intend to cover

all forms and arrangements which come within the definitions of my invention constituting the appended claims.

I claim:

- 5 1. In a controller, a valve casing, two plug valves mounted in said casing with their long axes parallel, and an interlock arranged between said valves to permit one of the valves to be operated freely when the second valve is in a neutral position and prevent the operation of the first valve when the second valve is at either limit of its movement.
- 10 2. In a controller, a valve casing, two plug valves mounted in said casing with their long axes parallel, an interlock arranged between said valves to permit one of the valves to be operated freely when the second valve is in a neutral position and prevent the operation of the first valve when the second valve is at either limit of its movement, and operating handles for said valves, the handle for said second valve being detachable and being interlocked with the casing to permit its removal only when its valve is at one limit of its movement.
- 15 3. In testimony whereof, I sign this specification.

HERBERT E. VAN DORN.
